UNITED STATES PATENT OFFICE

MARCUS MAZER, OF PHILADELPHIA, PENNSYLVANIA

ACOUSTIC SLAB

Application filed September 13, 1929. Serial No. 392,316.

The present invention relates to the art of acoustics, and has for an object to provide a building element of stone, stone composition or other suitable hard substance or composition providing a permanent depressed or indented surface structure incapable of being deformed, the depressions or indentations having a definite predetermined co-efficient of absorption.

10 It is well known that architects, builders and owners often require stone slabs as a veneer on the inside of their concrete walls, and since these stone slabs are very great reflectors of sound, it is an object of this invention to provide a slab embodying the above characteristics which will enable the architects, builders or owners to carry out their desires of stone slab construction and at the same time to secure perfect acoustic 15 properties in their building.

Another object of the present invention is to provide a slab or the like adaptable to any desired color or design, with an exposed surface in which are formed depressions or indentations to the desired number per square foot and which may be varied in size so as to give each square foot of the slab a predetermined acoustic value. The purpose desired is to enable the manufacture of slabs 20 which may be of the same size but which may have greater or lesser absorbing value. Also, the purpose is to enable the manufacture of these slabs where the indentations or depressions will present certain designs or configurations.

Another object of the invention is to provide an acoustic surface which may be incorporated in a building unit of any configuration and adapted for incorporation in a 25 wall or the like of practically any construction where units are employed, and wherein the units may be of any desired size so as to conform with regulation or standard requirements of slabs, blocks or the like.

Various other objects and advantages of this invention will appear from the following detailed description of the present shown embodiment, the same being illustrated in the accompanying drawings, wherein:

50 Figure 1 is a perspective view of an acoustic

slab constructed according to the present invention and showing a relatively large number of indentations or depressions to the square foot to impart a certain predetermined acoustic value to the slab.

Figure 2 is a vertical section taken through the same, showing the depressions in the exposed surface of the slab.

Figure 3 is a perspective view of a modified form of the acoustic slab wherein a relatively large number of depressions or indentations are formed in the outer or exposed surface of the slab for imparting an acoustic value to the slab differing from that of the slab of Figure 1, and

Figure 4 is a fragmentary enlarged face view of one corner of the slab, showing a modification in the shape of the depressions or indentations which are formed in the face thereof.

Referring now to the drawings, and first to the form of the invention shown in Figures 1 and 2, 10 designates the body portion of an acoustic slab which may be of suitable dimensions, and which preferably is about 1" in thickness. The acoustic slab may be made of any suitable material; one form being a suitable mineral plastic material, precast and dried or baked with certain depressions or indentations 11 in its outer or exposed face 12 which have a definite predetermined co-efficient of absorption. As shown in Figures 1 and 2 these depressions or indentations 11 may be of any desired number and depth within a given surface area, such as per square foot, and such depth and number of the openings 11 may be standardized so that the degree of absorption of these slabs may be known and they may be installed accordingly.

From Figure 2 it will be noted that the openings 11 are of sufficient depth only to provide the necessary air cushioning pockets, the depth being varied according to the diameter and number of openings 11 used to maintain a predetermined co-efficient of absorption, and from Figure 4 it will be noted that the shape of the openings may be varied at will for the purpose of ornamentation or to otherwise produce different results. Another feature of the openings 11 in the face

12 of the slab, is that the openings, indentations or other surface depressions or interruptions of the slab may vary in shape, width, length, depth or diameter, according to the 5 general configuration desired, in the same block or slab, or the opening 11 in each slab may be all of the same diameter and depth. The openings 11 may also be arranged as desired relatively to one another so as to produce 10 various designs or configurations on the face 12 of the slab to properly absorb sound.

By having the body portion of the slab 10 of a dense and rigid material it has a very low and practically negligible sound absorbing 15 quality and is rigid and permanent as to shape and density. The provision of the indentations 11 in the face 12 of the slab 10 effects a mechanical means of absorption which is positive and permanent and which, when once 20 ascertained with a certain number and size of indentations for a given surface area of slab, may be definitely used to various degrees for obtaining a desired co-efficient of absorption.

It is a well known fact that co-efficients of 25 absorption of materials are at the present time being scientifically ascertained by means of instruments made for that purpose.

The co-efficient of absorption of each slab 10 is determined by the number, depth and 30 diameter of the indentations or openings in the face 12 of the slab. By changing the number, depth and diameter of the indentations 11 in any given area, the co-efficient of absorption 35 is naturally changed.

When, by experiment, it is found that a 40 certain number of indentations of a known depth and diameter produce a definite co-efficient of absorption in one slab, for example; 45 percent absorption, other slabs with higher and lower coefficients of absorption, for example; 50 or 30 percent absorption, may be 45 constructed with a proportionately greater or lesser number of the openings of the first slab.

This change in the co-efficient of absorption 50 may also be effected by changing the relative depth or diameter or shapes of the indentations without changing the number thereof.

When the number of indentations of a given diameter and depth is determined for 55 a given surface area of slab, any number of slabs may be constructed accordingly, and all of these slabs will have the identical co-efficient of absorption.

In Figure 3 the modified construction of 60 acoustic slab 13 has in its outer face 14 a relatively large number of openings or indentations 15 per square foot as compared with the number of openings 11 in the slab 10 shown in Figure 1. The slab 13 therefore possesses 65 a different co-efficient of absorption than does the slab 10, and is also made standard so that the slabs 10 or 13 may be selected according to the degree of absorption desired in the face of the wall. It is of course understood that any desired number of stand-

ard slabs may be manufactured and the same may be used as selected in a wall structure as necessity demands for establishing desired, and correcting any defects, in the acoustic 70 properties of the building.

In the enlarged fragmentary view, Figure 75 4, the openings 16 in the face of the slab 17 are relatively large and are of polygonal form, and it is understood that the openings 16 may be of any desired shape or configuration for ornamental or other purposes.

The structure of this fire-proof, non-deformable, hard and unyielding slab is such that the depressions 11 cannot be altered as to size or shape by pressure on or against the slab, nor by rubbing over the surface of the slab; the slab therefore possessing a permanent predetermined and definite co-efficient of absorption.

By means of this invention definite and 85 permanent results are obtainable for desirable hearing conditions in a room.

The slabs 10, 13 and 17 may be of any suitable configuration at their inner or rear sides for securing the slabs to the inner sides 90 of concrete walls or the like, and that in other respects the slabs may be of standard materials, shapes or construction.

What is claimed is:

1. An acoustic slab, comprising a dense, 95 rigid body portion of fire-proof material having substantially a minimum inherent co-efficient of sound absorption, said body portion having in its exposed face a predetermined number of indentations of a depth and size proportioned to the absorptive quality desired, whereby to produce an acoustic slab having a permanent and fixed co-efficient of absorption and which is unalterable in handling and use.

2. An acoustic slab comprising a tile body portion presenting a sound reflecting outer face, and predetermined and permanent means for imparting a desired co-efficient of absorption to the slab, said means consisting of a rigid and dense outer face portion on the tile body having indentations therein selected as to depth, diameter and number to impart the desired co-efficient of absorption to the slab.

In testimony whereof I affix my signature.
MARCUS MAZER.
